UNITED STATES PATENT OFFICE.

RICHARD L. LEO, OF NEW YORK, N. Y.

BATH-CLOSET.

1,003,763.

Specification of Letters Patent. Patented Sept. 19, 1911.

Application filed April 22, 1910. Serial No. 556,962.

To all whom it may concern:

Be it known that I, RICHARD L. LEO, of New York city, in the county of New York and in the State of New York, have invented 5 a certain new and useful Improvement in Bath-Closets, and do hereby declare that the following is a full, clear, and exact description thereof.

My invention relates particularly to the 10 provision of a bath closet in a wall of extreme thinness; my invention being designed for the purpose of providing a bath closet of such dimensions that it may readily be installed in a thin partition wall, the 15 thickness of which is usually six inches.

The object of my invention is not only 20 to provide a bath closet of such dimensions that it may be installed in a partition wall of the thickness referred to, but which is exceptionally easy to operate, while at the 25 same time it is provided with all of the requisites of the usual shower bath and a shallow plunge bath, the latter having a depth as great as the thickness of the wall 25 will permit.

A further object of my invention contemplates the provision of a series of such 30 bath closets in an apartment house, the bath closets being located in adjoining rooms in the same partition wall which separates said adjoining rooms and being so located that the bath closets on succeeding floors over-lie one another.

I have shown one embodiment of my invention in the accompanying drawings, in 35 which—

Figure 1 represents a front elevation of 40 one of the bath closets showing the parts ready for use; Fig. 2 is a plan view of the same showing the parts in the same position; Fig. 3 is a horizontal cross-section of two adjacent bath closets, and Fig. 4 is a vertical section of a portion of an apartment house showing the bath closets of succeeding 45 floors.

In the drawings, 1 is a partition wall having a closet 2 therein. The closet 2 is provided with a door-frame 3 and a door 4 in the usual manner. It will be noted that 50 the closet 2 is provided with side recesses 5. At the upper portion of each of the recesses 5 there is located a hollow journal bearing 6 which is secured by means of screws 7 to the interior of the closet. Each 55 of the journal bearings 6 is provided with a horizontal extension 8 to receive the end of a pipe 9 bent in the shape of a bail and being provided with horizontal ends 10 for extending into the horizontal extension 8. The pipe 9 is connected at its center with a radially-directed pipe 11 which carries upon its end a shower bracket 12 of the usual type. A pipe 13 conveys water to the extension 8 through one of the journal bearings 6, whence the water passes through the pipe 9 and the pipe 11 to the shower bracket 12. A pair of curtains 14 are designed to be supported upon the pipe 9 and upon the horizontal extensions 8, the curtains 14 being so arranged that while in use they extend around the two sides of the pipe 9 to the pipe 11 where the adjacent ends of the two curtains may be connected together by means of button fastenings 15. An eye 16 is connected to the pipe 9 where it joins the pipe 11, which eye has attached thereto one end of a chain 17 which passes over a pulley 18 carried in the top of the closet 2, the other end of the chain 17 being provided with a handle 17' and hook 18' which is designed to be received upon a rod 19 secured at its ends to the interior of the closet, the rod 19 being designed in part to be used as a towel rack.

The pipe 13 extends downwardly in the recess 5 to a position approximating the center of said recess where the pipe 13 is provided with a hand-operated valve 20 for controlling the supply of water to the shower 12. Beneath the valve 20 there are located two valves 21 which lead respectively from hot and cold water pipes 22 and 23. Beneath the valves 21 there is a valve 24 which controls the supply of water to a shampoo attachment 25, a bracket 28^a being provided for supporting the shampoo attachment 25 when not in use. At the bottom of the closet there is located a pan 27 having a flat bottom 28, a flat rear portion 29, inclined sides 30 and a flat front portion 30'. The rear portion 29 extends downwardly above the level of the floor and is rabbeted at 31 at its top portion to receive the lower edge of tiling 31' which is carried by the rear wall of the bath closet. The tops of the two inclined sides 30 are also rabbeted at 32 in a similar manner and for a similar purpose. The bottom 28 of the pan is attached to a drain pipe 33, which connects with a trap 33' of the usual type. The up- 110

per front edge of the front portion 30' is hinged at 34 to the lower rear edge of a rectangular receptor 35 which has a horizontal drain pipe 36 which leads to the pan 5 located at the bottom of the closet which may be closed with a stopper 36' when it is desired to retain the quantity of water in the receptor 35. At the front of the receptor 35 there is located a handle 37 for convenience in elevating and lowering the receptor.

Reference being had particularly to Figs. 3 and 4, it will be seen that I locate two of such bath closets 2 and 38 in a single partition which separates adjoining rooms, the bath closets opening respectively into the adjoining rooms, the hot and cold water pipes 22 and 23 passing between the adjacent sides of the two bath closets. I also 10 locate, in the case of apartment houses, bath closets of this type in serial order above one another so that vertical supply pipes 39 may be used for connecting with the hot and cold water pipes 22 and 23 running 15 upwardly through the partitions between the adjacent closets. The outlet portions of the traps 33' are connected by horizontal pipes 40 with a vertical drain-pipe 41 running parallel to the pipes 39 located between the adjacent closets. The upper portions of the traps 33' are connected by means of horizontal pipes 42 to a vertical vent pipe 43 which is located adjacent to the pipes 39 and 41.

35 In the operation of the bath closet, when the closet is not in use, the pan 35 is folded upwardly against the rear wall 31'; the curtains 14 are supported in the recesses 5 upon the horizontal extension 8 and the 40 horizontal portions 10 of the pipe 9; the pipe 9 is in a position in which it hangs down vertically from the journal bearing 6; and the door 4 is closed. If now it is desired to use the bathing apparatus in the 45 closet, the door 4 is opened, the chain 17 is pulled downwardly by means of the handle 17' and the hook 18' is caused to engage with the horizontal rod 19, thereby moving the pipe 9 into a horizontal position. 50 The pan 35 is then moved downwardly until it rests upon the floor of the room and the curtains 14 are moved outwardly upon the pipe 9 until the space above the pan 35 is entirely inclosed, the bottoms of the curtains 55 falling within the pan. If it is desired to completely inclose the space above the pan, the curtains 14 can be buttoned together by means of the button devices 15. The water can now be caused to pass through the 60 shower 12 by turning on the valves 21 to supply the proper mixture of hot and cold water to the valve 20 which conveys water of the proper temperature to the pipes 13 and 9, the water passing from the pipe 9 through the pipe 11 to the shower 12. If it

is desired to take a plunge bath, the stopper 36' is inserted in the pipe 36 until a sufficient quantity of water has accumulated. If, however, it is desired to take merely a shower bath, the stopper 36' is removed from the 70 pipe 36. The shampoo attachment 25 can be used at any time by turning on the valves 21 and the valve 24 and removing the attachment 25 from the bracket 26. The water which escapes from the pipe 36 is conveyed 75 to the receptor 27 whence it flows through the trap 33' to the waste pipe 41, the trap 33' being vented at all times through the pipe 43.

The bathing apparatus is moved into its closed position by first moving the curtains 80 14 rearwardly into the recesses 5, then raising the pan 35 into a vertical position and finally lowering the pipe 9 by disengaging the hook 18' from the rod 19. The door 4 may then be closed to conceal the apparatus from view.

While I have described my invention above in detail, I wish it to be understood that many changes can be made therein without departing from the spirit of the 90 invention.

I claim:

1. In a device of the character described, a curtain, a pivoted rod adapted to hold the curtain, a portion of the rod being 95 adapted to hold the curtain in a line with the axis of the pivot.
2. In a device of the character described, a closet having a side recess, a curtain, a pivoted rod adapted to hold the curtain, a 100 portion of the rod being adapted to hold the curtain along the axis of the pivot and extending into said side recess.
3. In a device of the character described, a curtain, a hollow rod attached to a wall 105 for supporting said curtain, said rod being pivoted upon a horizontal axis parallel to the wall, a shower bracket connected to said rod and extending behind the curtain and connections for supplying water to said rod. 110
4. In a device of the character described, a curtain, a pivoted hollow rod in the shape of a bail for supporting said curtain, a shower bracket connected to said rod and extending behind the curtain and connections for supplying water to said rod. 115
5. In a device of the character described, a closet having a side recess, bathing attachments including a curtain and a rod adapted to hold the curtain and extending into said 120 side recess to permit the curtain to be moved out of view.
6. In a device of the character described, a closet, bathing apparatus therein, a pan at the bottom of the closet to receive the 125 waste water and a lining for the closet, said pan having its upper edge rabbeted to fit beneath the lining.
7. In a device of the character described, a closet having a side recess, bathing appa- 130

ratus in said closet and a pan at the bottom of the closet to receive the waste water, said pan extending into the side recess.

8. In a device of the character described, 5 a curtain, a pivoted hollow rod for supporting said curtain, a shower bracket connected to said rod and extending behind the curtain, connections for supplying water to said rod and means for raising and lowering said 10 rod and shower bracket.

9. In a device of the character described, 15 a curtain, a pivoted hollow rod in the shape of a bail for supporting said curtain, a shower bracket connected to said rod and extending behind the curtain, connections for supplying water to said rod and means for raising and lowering said rod and shower bracket.

10. In a device of the character described, 20 a curtain, a pivoted hollow rod for supporting said curtain, a shower bracket connected to said rod extending behind the curtain,

connections for supplying water to said rod and means for raising and lowering said rod and shower bracket and a towel rack for 25 holding said rod and shower bracket in their elevated position.

11. In a device of the character described, a curtain, a pivoted hollow rod in the shape of a bail for supporting said curtain, a 30 shower bracket connected to said rod extending behind the curtain, connections for supplying water to said rod and means for raising and lowering said rod and shower bracket and a towel rack for holding said 35 rod and shower bracket in their elevated position.

In testimony that I claim the foregoing I have hereunto set my hand.

RICHARD L. LEO.
